UNITED STATES PATENT OFFICE.

WILLIAM HECKMANN, OF IRVINGTON, NEW JERSEY.

SEALING-CAP-ATTACHING APPARATUS.

1,394,686.

Specification of Letters Patent.

Patented Oct. 18, 1921.

Application filed April 20, 1921. Serial No. 462,792.

To all whom it may concern:

Be it known that I, WILLIAM HECKMANN, a citizen of Germany, residing at Irvington, in the county of Essex and State of New Jersey, have invented certain new and useful Improvements in Sealing-Cap-Attaching Apparatus; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally, to improvements in stopper or cap-attaching devices; and, the present invention has reference, more particularly, to a novel and simply constructed apparatus which is especially adapted for use in securing the usual crimped metallic stopper-caps to the mouths of bottles.

20 The present invention has for its principal object to provide a novel and simply-constructed capping device, provided with means for its attachment to a bench or table, the device being readily operated, and is of such construction that the crimped metallic cap is quickly and positively secured upon the mouth of the bottle.

Other objects of the present invention not at this time more particularly enumerated will be clearly understood from the following detailed description of the present invention.

With the objects of the said invention in view, the invention consists, primarily, in the novel capping apparatus hereinafter more fully set forth; and, the said invention 40 consists, furthermore, in the general arrangements and combinations of the several devices and parts, as well as in the details of the construction of the said parts, all of which will be more fully described in the following specification, and then finally embodied in the clauses of the claim which are appended to and which form an essential part of the said specification.

The invention is clearly illustrated in the accompanying drawings, in which:—

Figure 1 is an elevation of the capping apparatus, showing in connection therewith, a bottle in its clamped relation to the apparatus, with the crimped sealing cap secured over the mouth of the bottle; and Fig. 2 is a vertical sectional representation of the sev-

eral parts, said section being taken on line 2—2 in Fig. 3, looking in the direction of the arrow α in Fig. 1.

Fig. 3 is a horizontal sectional representation of the apparatus and of the inserted bottle, when in the position ready to receive the sealing cap, said section being taken on line 3—3 in said Fig. 1, and said view being made on an enlarged scale; and Fig. 4 is a similar view of the same parts, said view, however, showing a pair of articulating clamping jaws in their opened positions ready for the reception of the neck of the bottle, prior to being moved into the cap-receiving position with the main body or frame of the apparatus.

Similar characters of reference are employed in the said above described views, to indicate corresponding parts.

Referring now to the several figures, the reference-character 1 indicates a complete capping apparatus made according to and embodying the principles of the present invention, the said apparatus comprising a main body or base 2, formed with a receiving opening 3, substantially of the configuration shown in Fig. 4 of the drawings, and provided at one side with suitably formed clamping members, as 4 and 5, the member 5 being formed with a screw-threaded portion or boss 6 in which is movably disposed the screw-threaded portion or boss 6 in which is movably disposed the screw-threaded shank 7 of a tightening or clamping screw, as illustrated in Fig. 1 of the drawings, for attachment of the capping apparatus to the member 8 of a suitable work-bench or table. Extending upwardly from the said main body or base 2 is a frame-work comprising a pair of standards, as 9 and 10, which are suitably connected by means of laterally extending members 11 and 12, said members being formed with tubular parts 13, providing a pair of bearings in which is movably mounted a capping stem or plunger, as 14. That portion of the plunger or stem 14 which is located between the said laterally extending members 11 and 12, is encircled by a coiled spring 15, said spring having its lower end resting upon the upper surface of the laterally extending member 12, and the upper end of said spring bearing against a pin 16, substantially as shown in Figs. 1 and 2 of the drawings. The lower end-portion of the plunger or stem 14 projects beneath the lower surface of the said

75

105

110

115

laterally extending member 12, and suitably secured to said lower end of said plunger or stem is a chambered or cup-shaped member, as 17, the purpose of which will presently be 5 more fully set forth. In order to produce reciprocatory movement of the said plunger or stem 14, one of the standards, as 10, is provided with a perforated lug 18, to which is pivotally connected, by means of a pivot- 10 pin 19, the one end portion of a link 20, the other end-portion of said link being pivotally connected by means of a pin 21 with the end-portion 23 of an operating lever 22, the said lever being operatively connected 15 by means of a fulcrum-pin 24 with the upper end-portion of the stem or plunger 14, substantially in a manner as shown in said Figs. 1 and 2 of the drawings. Upon its free end-portion the said lever 22 is provided with a 20 suitable operating handle 25.

The previously mentioned articulated clamping jaws for receiving the neck-portion 27 of the bottle 26 which is to be capped, is shown more particularly in Figs. 3 and 4 25 of the drawings, the same comprising two arc-shaped elements, as 28 and 29, the member 28 being pivotally mounted upon the upper surface of the body or base 2 of the device, by means of a pivot-post or pin 30. 30 The said member 28 is also provided with a suitable extension, as 31, to the free end-portion of which is pivoted, by means of a rivet or pin 32, an extension 33 with which the other member 29 is provided, as indicated in dotted outline in said figures. 35 When the two arc-shaped members 28 and 29 are brought into their closed relation, the concave and semi-circular open portions 34 and 35 of the respective members 28 and 40 29 will form a ring-shaped bottle-holding attachment, as will be evident, and when moved directly over the opening 3 of the said body or base 2, the marginal portion 36 of the member or element 29 will ride directly beneath a hook-shaped lug, as 37, 45 with which the said body or base 2 is provided, a projection 38 which extends from said member or lug 29, serving as a stop to bring the central opening of the ring-shaped 50 attachment thus provided, directly over the opening 3, as will be clearly evident from an inspection of said Fig. 3 of the drawings.

Having in the foregoing described the general construction of a capping apparatus, showing one embodiment of the principles of the present invention, I will now briefly set forth, the manner of using the device for securely attaching a crimped metal sealing cap, as 39, over the mouth of 60 a bottle.

In order to accomplish this, the jaws or members 28 and 29 are moved from their closed relation represented in Fig. 3 of the drawings, to the opened positions indicated 65 in Fig. 4. The neck of the bottle is now

placed against the edge-portion 40 of the extension 31 of the member 28. By now pushing the bottle in the direction of the arrow y, see Fig. 4, the marginal edge-portion 36 of the member 29 is caused to ride 70 against the standard 10, causing the said members 28 and 29, as soon as the bottle has moved into the opening 3, to completely embrace the neck of the bottle, thereby positively holding the bottle in its suspended 75 position, with the closed clamping jaws retained in their bottle-clamping relation, against displacement, by the headed pivot-post 30 and the engagement of the hook-shaped projection 37 with the marginal 80 edge-portion 36 of the jaw or member 29, as will be clearly understood from an inspection of said Fig. 3 of the drawings.

The metal sealing cap 39 is now placed over the mouth-portion of the neck of the 85 bottle, and the lever 22 by means of the handle 25 is pressed in a downward direction.

The action causes the stem or plunger to be moved in a downward direction against 90 the action of the spring 15, whereby the cup-shaped member 17 forcibly presses the cap 39 down over the mouth of the neck of the bottle, and tightly seals the same against accidental displacement, as will be evident. 95

To prevent a metal sealing cap from becoming jammed in the cup-shaped portion or depression of the member 17, the laterally extending member 12 has secured thereto one or more pins or stems, as 41, the lower- 100 end portions of which extend, when the parts are in their normal positions, indicated in Figs. 1 and 2, through correspondingly disposed holes or perforations 42 in the top of the said member 17, and project directly 105 into the chambered part of the said member, as shown.

Thus it will be evident, that in case a sealing cap 39, during the downward stroke of the apparatus, for some reason does not 110 attach itself to the mouth of the neck of the bottle, it can not become jammed within the said cup-shaped member 17, since during the return stroke of the parts and the upward movement of the member 17 upon 115 the fixed pins or stems 41, the latter engage the sealing cap and thereby forcibly expel the same from the cup-shaped portion or depression of said member 17.

Of course I am aware that some changes 120 may be made in the general arrangements and combinations of the various devices and parts, as well as in the details of the construction of the said parts, as set forth in the foregoing specification, and as defined 125 in the clauses of the claim which are appended thereto. Hence, I do not limit myself to the exact arrangements and combinations of the several devices and parts, as described in the said specification, nor do I 130

confine myself to the exact details of the construction of the said parts, as illustrated in the accompanying drawings.

I claim:—

ing members being provided with receiving bearings, a bottle-holder comprising a pair of pivotally connected bottle-clamping jaws adapted to embrace the neck-portion of the bottle, means for pivotally attaching one of said jaws to said base, a hook-shaped projection extending from said base beneath which a portion of the other jaw is adapted to be moved into engagement, a plunger 10 movably disposed in said bearings, a cup-shaped end-member connected with said plunger, said end-member being provided with pin-receiving perforations, means for

actuating said plunger, and ejector-pins projecting from the lower one of said laterally 15 extending members between said standards, said ejector-pins extending into and through the perforations of the end-member of said plunger.

In testimony that I claim the invention set 20 forth above I have hereunto set my hand this 14th day of April, 1921.

WILLIAM HECKMANN.
